UNITED STATES PATENT OFFICE.

JOHN GOOD, OF BROOKLYN, NEW YORK, ASSIGNOR TO GOOD INVENTIONS CO., OF NEW YORK, N. Y., A CORPORATION OF NEW YORK.

INTERNAL-COMBUSTION ENGINE.

Application filed May 9, 1919. Serial No. 295,952.

To all whom it may concern:

Be it known that I, JOHN GOOD, citizen of the United States, residing in Brooklyn, New York, have invented the following described Improvements in Internal-Combustion Engines.

The invention provides a simple means of eliminating certain objectionable conditions in the operation of internal combustion engines, its objects being to establish by independent combustion, and maintain when necessary, a proper working temperature in the crank case and cylinder walls of automotive engines, thereby permitting the engine to be readily cranked and started even in the coldest weather and without danger of breaking the oil or water pump if frozen, at the same time serving to eliminate or prevent contamination of the lubricating oil in the crank case by liquid fuel escaping past the piston rings, and thereby also insuring prompt distribution of the lubricating oil to all the bearings of the engine.

In the accompanying drawings,

Fig. 1 is a side elevation of so much of an engine as is necessary to comprehend the invention, with a diagram of the burner connections for the purposes stated;

Fig. 2 is a partial cross-section of the engine; and

Fig. 3 a horizontal section on line III—III of Fig. 2.

These drawings represent a conventional automobile engine of four cylinders, cast in block and formed with a flame pipe or passage 1, extending from a coupling flange at one end of the block along the side of the block through the several water-jacket spaces of the several cylinders, around the end of the block and back through the jacket spaces on the opposite side to an off-take pipe 2 which may be extended to the engine exhaust pipe or elsewhere, preferably outside the engine compartment.

Flame and hot combustion products are delivered into this pipe through a fitting 3 from an enclosed burner 4, operated in the present case by a fan 5, the latter being driven by a motor 6 connected to the starting battery and controlled by a switch 7. Fuel is supplied to the burner head through the regulable connection 8, from the float bowl of the engine carburetor 9, and a spark plug 10 in proper circuit with the

battery and a spark coil 11 serve automatically to ignite the fuel in the enclosed burner whenever the switch is closed to start the fan motor in operation. Such burners as herein shown are known to the art and any suitable type of enclosed mechanism, operated by forced draft or by suction may be used in its stead. When the burner head 4 is in action, flame or combustion products therefrom traversing pipe 1, heat the water in the jacket space or spaces and thereby quickly produce a working temperature therein. It is obvious that the passage 1 can be incorporated in or associated with the jacket structure in a variety of different ways to transmit heat to the water therein or otherwise heat the cylinder wall adjacent the combustion space.

A second passage 12 extends from the fitting 3 alongside of and around the barrels of the several cylinders below their combustion spaces or water-jackets, being substantially parallel to the pipe 1, with an outlet on the opposite side into the same off-take pipe 2. A portion of the flame and combustion products from the burner mechanism traversing this passage heats the cylinder barrels and serves the double function of softening the lubricating oil on the inner surfaces thereof in cold weather, which establishes a normal condition of lubrication. As in the case of the pipe 1, this passage may also be variously incorporated in or applied to the cylinder structure for the purposes stated.

Still another passage 13 extends from the fitting 3 downwardly around the lower side of the crank case, surrounding the chamber of the oil pump 14 and extending thence under the bottom of the crank case and upwardly on the other side to a connection 18 with the offtake 2 as in the case of the other passages. The portion of the flame or combustion products which passes through this passage 13, besides warming the interior lubricating oil contained in the crank case, more particularly serves to reduce the viscosity of the oil in the oil sump so that it is instantly ready to flow freely through the various oil tubes (not shown) and if any collected water has frozen in the pump as is frequently the case, it is melted and the pump is therefore not likely to be broken from attempted operation when frozen. In

the same way the water pump, being located close to the jacket (but not herein shown) is similarly protected.

All the passages are desirably made of thin walls and pass through or in heating relation to the engine structure without interfering with other engine parts. One or more of them may be omitted according to the effects required and the fitting 3 10 may have any desired shape according to the selected location of the burner mechanism, regard being had to the proper distribution of the flame into each passage when a single burner is used to supply them 15 all with flame or combustion products. No attempt is made in the accompanying drawings to illustrate any preferred location of the burner mechanism, as this is obviously controlled by the general design of the power plant as a whole, which will vary widely 20 in different cases. The controlling switch 7 is preferably located within convenient reach of the operator so that on such occasions as the engine may require it the supplemental source of heat can be brought into 25 action and used for as long as may be necessary to produce the results desired. Such switch may obviously be thermostatically controlled in any usual manner. Valves 16 30 and 17 are provided in the fitting 3 so that all of the flame may be delivered to either passage. These valves are indicated in dotted lines in Fig. 1 and are equipped with appropriate exterior crank connections where- 35 by they may be set to appropriate positions for controlling the entrance for the flame or combustion products to the passages, as will be understood without description, and it will be plain that all or a predominating 40 part of the entire flame from a single burner may if desired be sent through any passage,

whether the engine be running or not, by a proper setting of both of them, and that a single flame may be distributed in varying proportion to the several passages. 45

Claims:

1. In an internal combustion engine, a water-jacket or water jackets surrounding the cylinder combustion space or spaces, a passage alongside the cylinder or cylinders 50 between the water-jacket and the crank case, and means independent of the combustion in the engine for passing a heating medium through said passage.

2. In an internal combustion engine, the 55 combination of a heating passage in heat transferring relation to lubricated or lubricant-containing walls of the engine structure, an electrically controlled burner for passing a heating medium through said passage, and a switch for controlling the operation of the burner, said switch being located within the convenient reach of the engine operator. 60

3. In an internal combustion engine, the 65 combination of a cylinder or cylinders, an oil pump, a liquid fuel burner having means to supply the same with air under pressure, and an outlet passage for the flame and combustion products of said burner extending to said oil pump. 70

4. In an internal combustion engine, the combination of a cylinder or cylinders, an oil pump, a liquid fuel burner, means for supplying the same with air under pressure, 75 an outlet passage from said burner extending into heating relation to a plurality of lubricated surfaces in the engine and to said oil pump.

In testimony whereof, I have signed this 80 specification.

JOHN GOOD.
